INCINERATOR FOR PRODUCTS OF COMBUSTION ENGINES, FURNACES, AND THE LIKE

Carl Bellstedt, Lynwood, Calif.

Application November 15, 1945, Serial No. 628,692

1 Claim. (Cl. 183—6)

1

The invention relates to an incinerator, and more especially to a burner for exhaust from an internal combustion engine or other types of motors having exhaust products.

The primary object of the invention is the provision of a burner of this character, wherein the fumes or other matter which are exhausted from an engine, other exhaust medium, or the like will be burned, either to provide heat or to purify the exhaust of its poisonous and obnoxious ingredients, the burner being designed for use in shops, factories, public buildings, garages or the like where the smoke, fumes or carbon monoxide may be present for the elimination thereof from the enclosure.

Another object of the invention is the provision of a burner of this character, wherein the construction thereof permits use on internal combustion engines, Diesel motors or any other power unit using combustible fuel, the burner being of novel construction and is unique in the arrangement and assembly of parts thereof.

A further object of the invention is the provision of a burner of this character, which is simple in construction, thoroughly reliable and efficient in operation, functioning as an incinerator, strong, durable, automatic in the working thereof, and inexpensive to manufacture and install, it being safe for the elimination of dangerous gases, fumes and smoke.

With these and other objects in view, the invention consists in the features of construction, combination and arrangement of parts as will be hereinafter more fully described, illustrated in the accompanying drawing, which discloses the preferred embodiment of the invention, and pointed out in the claim hereunto appended.

In the accompanying drawing:

Figure 1 is a side view, partly broken away, of the burner constructed in accordance with the invention;

Figure 2 is a view of the front end of the burner;

Figure 3 is a sectional view taken substantially on the line 3—3 of Figure 2 looking in the direction of the arrows with the feed nozzle in elevation;

Figure 4 is a sectional view taken on the line 4—4 of Figure 1 looking in the direction of the arrows;

Figure 5 is a sectional view taken on the line 5—5 of Figure 1 looking in the direction of the arrows.

Similar reference characters indicate corre-

2

sponding parts throughout the several views in the drawing.

Referring to the drawing in detail, the burner constituting the present invention, comprises a cylindrical shell or casing 10, forming therein an explosive chamber 11, and in the cylindrical walling of this shell or casing perforations or vents 12 opening into the said chamber, while opening through an end head 13 to this shell or casing is a choke funnel or conduit 14, which tapers in the direction of such head. The funnel or conduit 14 leads from a mixing bowl or drum 15 into which is partially extended a pipe 16. On the exterior of the pipe 16 is fixed a disk-like baffle 17, spaced from and confronting air inlets 18 of the bowl or drum 15. This exhaust pipe 16 conducts spent or exhaust products of combustion from a combustible fuel operated or internal combustion engine, not shown, to the mixing bowl or drum 15 in the working of the burner for the elimination of obnoxious or poisonous fumes from such exhaust.

Opening into the combustion chamber or explosive chamber 11 is an elbowed burner nozzle or jet 19 which at its flame tip 20 axially aligns with the funnel or conduit 14 and directs the flame toward the entirely open end 21 of the shell or casing 10.

The shell or casing 10 is fitted with a tubular holder 22 for a spark plug or other ignition device 23 of the electrical spark gap type, yet in this connection there may be as a substitute a gas pilot or other igniter, the shell or casing 10 and the bowl 15 being provided with supporting standards 24 for the setting up of the entire burner heretofore described. The nozzle or jet 19 has support from a hanger 25 carried by the funnel or conduit 14, that is to say, the feed line 26 to this nozzle or jet being mounted to this hanger. The nozzle or jet 19 uses natural or manufactured gas supplied thereto by the feed line 26 from the source of supply in the operation of the burner.

The gas when ignited destroys all poisonous and obnoxious fumes from the exhaust admitted to the chamber 11 through the funnel or conduit 14 which takes such exhaust from the mixing chamber in the drum or bowl 15 delivered thereto by the pipe 16, the burner being usable in factories, shops, public buildings, garages, or anywhere that smoke, or other products of exhaust or carbon monoxide is present and must be eliminated.

The shell or casing 10 is also adapted for use

with a lining of fire brick for the purpose of retaining the heat that is formed from the action of the apparatus, and thus, when sufficiently hot, reduces the need for natural gas or other methods used to burn the exhaust, it being self operating. 5

What is claimed is:

A burner for utilizing exhaust gases from combustible fuel engines comprising a mixing chamber having air inlets open to the atmosphere, an intake pipe concentric with and extending into 10 said mixing chamber, said intake pipe being adapted for connection to the exhaust of the engine for conducting the exhaust products therefrom to said mixing chamber, a baffle disk mounted on said intake pipe in confronting relationship with the air inlets of said mixing chamber for governing the air supply thereto, a perforated cylindrical shell having one end enclosed by a head wall and its opposite end open to the atmosphere, a substantially truncated conical 20 funnel connecting said mixing chamber and said cylindrical shell at the head wall thereof for conducting the contents of said mixing chamber to said cylindrical shell, said funnel being tapered 25

in the direction of said cylindrical shell, a burner nozzle mounted in said cylindrical shell adjacent to and facing in the direction of movement of the discharge from said funnel, means supplying fuel to said burner nozzle for forming a flame thereat whereby the propagation of said flame is in the direction of the discharge from the funnel and toward the open end of the cylindrical shell, and electrical ignition means in said cylindrical shell adjacent said burner nozzle for igniting the flow of fuel therefrom, whereby the flame propagated from said burner nozzle will be introduced into the flow of discharge from the mixing chamber for causing combustion of the exhaust products.
